URINALYSIS DEVICE

Wolf Goodman, Houston, Tex., assignor to
 Southern Detector Corporation, Houston, Tex.,
 a corporation of Texas

Application April 20, 1946, Serial No. 663,742

4 Claims. (Cl. 23—253)

1

This invention relates to new and useful improvements in urinalysis devices.

One object of the invention is to provide an improved device for making an analysis of urine to determine the presence of sugar or albumin therein.

An important object of the invention is to provide an improved urinalysis device arranged to receive the specimen or sample to be tested and having means for mixing said specimen with the usual chemical reagents ordinarily employed for sugar and albumin tests; the chemical being in tablet form, whereby handling and introduction of the chemicals into the specimen is simplified and also whereby the proper amount of chemical is introduced and admixed with the specimen upon each operation of the device to assure accurate tests of said specimen.

Another object of the invention is to provide an improved urinalysis device which is entirely self-contained and which is automatic in its operation in accomplishing the tests for determining the presence of sugar and albumin in the specimen; the device being so constructed that it may either be started automatically by the insertion of a coin or may be manually started by an electrical push button or switch lever.

Still another object of the invention is to provide an improved device, of the character described, wherein the chemical reagent tablets which are introduced into the specimen to effect the tests are disposed within containers removably mounted within the device, the removability of said containers facilitating replacement thereof when said containers are emptied of their contents; the containers in which the tablets are disposed co-acting with a dispenser which is automatically controlled in its actuation to eject one tablet from each container upon each operation of the device.

A further object of the invention is to provide an improved device, of the character described, wherein the specimen is manually introduced into said device, after which a complete cycle of operation occurs automatically to make the tests, said cycle including the lighting of electrical lamps to increase visibility of the results of the test, the addition of the chemical reagents to the specimen, actuation of heating elements to heat the specimens after the chemicals are added, shutting off said heating elements, flushing fresh water through the unit after the test is complete, and finally extinguishing the electrical lamps, said cycle of operation being controlled by a single electrical timing motor, where-

2

by the construction of the device is simplified and efficient automatic operation is assured.

A particular object of the invention is to provide an improved urinalysis device, wherein the specimen being tested is clearly visible to the observer at all times, whereby the tests may be observed as they are being made and the results clearly seen; the device also including comparison colored lights which are located on the exterior of the device adjacent the viewing windows to facilitate the observer readily ascertaining the results of the tests. Of course, charts or other indicators may be used.

A still further object of the invention is to provide an improved device, of the character described, wherein all of the operating parts of the device are mounted on a single panel which is readily removable from the casing of said device as a unit; the tablet containers, as well as the test bulbs which receive the specimens, being further detachably mounted on the panel to permit their separate removal for replacement, cleaning or repair.

Another object of the invention is to provide an improved urinalysis device having means for accurately controlling the volume of urine which is introduced into the test bulb wherein the test for sugar presence is made since in such test, the volume of the specimen controls the color obtained after the chemical is added and heat applied; control of the volume in this manner assuring that accurate and consistent sugar tests will be made by the device.

The construction designed to carry out the invention will be hereinafter described together with other features of the invention.

The invention will be more readily understood from a reading of the following specification and by reference to the accompanying drawing, wherein:

Figure 1 is an isometric view of a urinalysis device, constructed in accordance with the invention.

Figure 2 is an elevation of the interior of the device, the hinged front of the casing being removed.

Figure 3 is a transverse, vertical, sectional view, taken on the line 3—3 of Figure 2.

Figure 4 is a horizontal, cross-sectional view, taken on the line 4—4 of Figure 3.

Figure 5 is a horizontal, cross-sectional view, taken on the line 5—5 of Figure 3.

Figure 6 is a vertical, sectional detail of the

slide dispenser in a position dispensing the tablet for the albumin test,

Figure 7 is a similar view, with the slide dispenser in a position dispensing the tablet for the sugar test,

Figure 8 is an isometric view of the slide ejector bar,

Figure 9 is an enlarged, sectional detail of the funnel which receives the specimen,

Figure 10 is an isometric view of one of the heater elements,

Figure 11 is a longitudinal, vertical, sectional view of said heater element,

Figure 12 is an isometric view of the timing motor, timing cams and control switches,

Figure 13 is a horizontal section, taken on the line 13-13 of Figure 12,

Figure 14 is a wiring diagram of the device, and

Figure 15 is a sectional view illustrating the substitution of a coin control for the push button shown in Figure 14.

In the drawings, the numeral 10 designates a casing or housing which is generally rectangular in shape and which has its front side open. The front side is adapted to be closed by a hinged cover 11 which is normally retained in a closed position by a suitable lock 12. The casing or housing is arranged to be attached to a wall in any desired manner or may be mounted by suitable brackets (not shown) on a support. The hinged cover or closure 11 is provided with a pair of viewing windows 13 and 14 which may be closed by transparent panes 15. As will be explained, the tests made by the device may be observed through the windows 13 and 14 and immediately above said windows is a pair of colored comparison lights 16 and 17. The colors of the lights are such as to facilitate an interpretation of the tests which are observed through the windows, as will be explained in detail. An electrical starting button 18 is also mounted in the hinged closure or cover 11 and manual depression of the button will place the apparatus into operation; if desired, the push button 18 may be eliminated and a coin slot provided so that the insertion of a coin may function to operate the device.

Within the interior of the casing or housing is mounted a main supporting panel 19, this panel being secured to the rear wall of the casing by means of spacer posts 20 and screws 21. A horizontal plate or support 22 is secured to the panel 19 by screws 23 and extends forwardly from said panel (Figure 3). An extension 24 which is preferably formed integral with the plate 22 extends forwardly from the horizontal edge of said plate and has a slot 25, rectangular in cross-section extending entirely therethrough. A slide bar 26 (Figures 6 and 7) is slideable within the rectangular slot 25 and this bar is provided with a circular opening 27 in one end thereof, with a similar opening 28 in its opposite end. As is clearly shown in Figures 6 and 7, the slide bar has a length which is greater than the length of the extension 24 and its slot 25, whereby the ends of the bar project beyond the ends of the extension. The slide bar 26 is adapted to be moved within the slot 25 by means of an electric relay or solenoid 29. The actuating arm 30 of the solenoid is connected by an angular link member 31 with an upright arm 32 which is formed integral with and extends upwardly from the slide bar 26. The angular link has an ear 33 to which one end of a coil spring 34 is connected and the opposite end of said spring is connected to a stationary post 35 which is se-

cured to the plate or support 22. The upright arm 32 of the slide bar moves within a slot 36 provided for this purpose in the top of the extension 24, whereby movement of the slide bar 26 is permitted when the solenoid 29 is energized to impart movement to its actuating arm.

It is apparent that the coil spring 34 constantly exerts its tension to hold the slide bar in the position shown in Figure 6, in which position the opening 27 is outside of the slot 25 within the extension 24. When the solenoid is energized, its actuating arm is drawn into the coils of said solenoid and the slide 26 is moved to the position shown in Figure 7. In such position 15 the opening 28 in the opposite end of the bar is moved out of the slot 25.

The slide bar 26 forms an ejector and said bar is adapted to co-act with chemical tablets A which are disposed within a tube 37 and also 20 with chemical tablets B located within a similar tube 38. The tube 37 has its lower end engaged within an annular recess 39 which is formed in the upper surface of the extension 24 within which the slide 26 is movable. The upper portion 25 of the tube 37 is clamped within a frictional spring clip 40 which is secured to the forward edge of a flat plate member 40a which extends forwardly from the upper portion of the main supporting panel 19. The lower end of the tube 38 is confined within an annular recess 41 also formed in the top of the extension 24, while the upper portion of said tube is retained within a spring clip 42 which is also secured to and extends forwardly from the edge of the supporting member 40a. It will be obvious that with this mounting of the tubes 37 and 38, said tubes may be readily and easily removed from their retained position, whereby replacement of said tubes is facilitated.

The tubes 37 and 38 are positioned so that the tablets which are located therein may pass downwardly from the tubes into the openings 27 and 28 of the slide 26. A circular opening 43 is formed in the extension below the tube 37 whereby the tablets A within the tube 37 may pass downwardly and engage the upper surface of the slide 26, as shown in Figure 6. A similar circular opening 44 is provided below the tube 38 so that the tablets B within said tube may pass downwardly and engage the upper surface of the slide, as shown in Figure 7. The spacing of the holes or openings 27 and 28 in the slide bar 26 is such that in one position of the slide, as shown in Figure 6, the opening 28 is immediately below the tube and in alignment with the outlet opening 44, whereby a tablet B may fall downwardly into the opening 28 of said slide bar. At this time the opening 27 is completely outside of the slot 25 of the extension 24. The tablets are of a height which is the same as the thickness of the slide bar so that the tablet will substantially fill the opening and will have its upper and lower surfaces lying flush with the top and bottom of the slide bar.

When the slide bar 26 moves from the position shown in Figure 6 to that shown in Figure 7, the tablet B which has entered the opening 28 will be moved outwardly of the slot 25 and will fall downwardly from the opening 28, whereby the tablet is ejected. At the same time that the tablet B within the opening 28 is ejected, the opening 27 moves into alignment beneath the outlet 43 and tube 37, whereby a tablet A from the tube 37 may enter the opening 27. Upon return of the slide bar to its original position (Fig.

ure 6), the tablet A which has entered the opening 27 will be ejected from said opening, in the same manner that the tablet B was ejected from the opening 28 in the opposite position of the slide bar. Thus, it will be seen that upon one complete reciprocation of the slide bar, one of the tablets A will be ejected from the tube 31 and one of the tablets B will be ejected from the tube 38. The operation is accomplished by momentarily energizing the solenoid 29 to implement movement to its actuating bar 30.

Each tablet A comprises a chemical which is suitable for an albumin test of a urine specimen. The particular tablet used is subject to variation since several known reagents may be used for this test. As an example, sulfasalicylic acid has been found to be entirely satisfactory because it can be readily compounded in tablet form which will dissolve quickly in the liquid. Each tablet B comprises a chemical which is suitable for a sugar test of a urine specimen and as is the case with respect to the tablets A, the tablets B are also subject to variation. As an example, the tablet B may contain Benedict's solution which has been found satisfactory for accurately testing for the presence of sugar. However, it is particularly pointed out that any material in tablet form capable of making sugar and albumin tests may be employed.

When the slide ejector is actuated to eject a tablet A from the tube 31 and a tablet B from the tube 38, the tablet A is arranged to drop into a test receptacle or bulb 45, while the tablet B drops into a test receptacle or bulb 46. The receptacles or bulbs 45 and 46 are constructed of glass or other transparent material and are made integral with a glass tubular element 47. Above the bulbs, the element 47 is formed with flared funnels 48 and 49 which have their upper ends open and which assure the entry of the tablets into the bulbs. The element 47 has a reduced inlet end 50 and an enlarged outlet end 51 and the element is supported in position below the slide ejector by means of spring clips 52 which extend forwardly from the main supporting panel 19. The inlet end 50 of the element 47 is connected to a water inlet valve 53, which valve is secured to the rear side of the panel 19. The valve 53 is electrically operated by a relay 54 which is built into the valve. Said valve also has connection with a water inlet pipe 55 which extends into the casing through the bottom thereof. A metering valve 56 may be connected in the inlet line 55. When the relay 54 is energized to open the valve 53, fresh water is introduced through the inlet 51 and flows through the element 47; in so doing this fresh water flushes out the bulbs 45 and 46. The flushing water is discharged from the discharge end 51 of the element 47 and into a discharge pipe 57 which extends downwardly through the bottom of the casing. A portion of the flushing water escapes from the central portion of the tubular element 47 through outlet 58 which has connection through a conductor 59 with the main discharge pipe 57. The relay actuated water valve is operated after the tests made by the apparatus are complete so as to thoroughly flush out the bulbs 45 and 46.

For introducing the specimen of urine to be tested into the apparatus, the tubular element is provided with a reduced, inverted T-shaped tube 60. One leg 61 of the tube 60 has its open end over-hanging the bulb 45. The opposite leg 62 of said tube (Figure 2) has its end formed

with a small flask 63 having a reduced opening 64 in its lower end. The flask 63 is of a predetermined size so that when the urine specimen is introduced into the inlet 60, a predetermined volume of the specimen will enter the flask 63; as is clearly shown in Figure 2, the flask has its major portion in a plane below the outlet end of the leg 61 of the tube and said outlet is of considerably greater area than the reduced escape opening 64 leading from the flask. Upon the initial introduction of the specimen liquid the tubular element 60 and flask will completely fill with said liquid and then the liquid within the tube 60 will escape through the outlet end of the tube. Because the flask is in a plane below the outlet end, the liquid in the flask will not flow upwardly into the tube 60 but can escape from the flask only through the reduced opening 64 into the bulb 46. The purpose of the reduced opening 64 is to impede the escape of liquid from the flask upon the initial introduction of liquid so as to momentarily hold substantially all of the liquid in the flask in order to allow sufficient time for the remainder of the liquid to flow from the larger outlet of the opposite leg 61 of the tubular element 60. From the flask the predetermined volume will flow into the test bulb 46 and in this manner the same amount of urine to be tested will be introduced into the bulb 46 upon each operation of the apparatus.

The inlet tube 60 is connected through a conductor 65 with the lower end of an inlet funnel 66, which funnel is mounted within an opening 67 (Figure 9) in the top of the casing 10. The funnel 66 is retained in position within the opening by suitable clamps 68 and the upper portion of the funnel has a circular spray tube 69 mounted therein. The spray tube has connection with an angular pipe 70 which extends downwardly through the wall of the funnel and this pipe is connected by a conductor 71 with the water inlet valve 53.

The specimen of urine is poured into the funnel 66 and flows downwardly through the conductor 65 into the inlet tube 60. Flowing through the legs of branches 61 and 62 of the inlet tube, the specimen enters the bulbs 45 and 46, the volume entering the latter bulb being controlled by the size of the flask 63 at the end of the leg 62 of said inlet tube. After the specimen has been introduced into the test bulbs 45 and 46, the ejector or slide bar 26 is actuated by energizing the solenoid 29 and a tablet A is thereby introduced into the bulb 45 and a tablet B is introduced into the bulb 46.

In order to properly accomplish the tests, it is necessary that heat be applied to the specimen under test and for this purpose, a pair of heaters 72 and 73 are provided. The heaters are constructed in an identical manner and are clearly shown in Figures 10 and 11. Each heater comprises a main body 74 having a recess 75 in its forward portion for receiving the test bulb. A heating wire 76 is engaged within longitudinal channels or grooves 77 formed in the wall of the recess 75 and obviously when current is passed through the heating wire, heat will be applied to the bulb disposed within the recess 75. The heaters are secured to the main supporting panel 19 by suitable screws 74a and the heater 72 surrounds the bulb 45, while the heater 73 surrounds the bulb 46.

The operation of the heaters 72 and 73 is electrically controlled so that after the ejector or slide bar 26 has actuated to deposit the tablets

A and B in the bulbs 45 and 46, the heaters are operated to apply heat to the contents of said bulbs. As the chemical reaction occurs, the color of the contents of the bulbs 45 and 46 will change. With respect to the bulb 45 which receives the tablet A for the albumin test, it is desirable to paint the rear surface of the bulb 45 black to facilitate determining results of the test. If no albumin is present in the specimen, the fluid remains clear in color and by painting the rear 10 of the bulb 45 black, the clearness of the fluid would not be visible so that in appearance the contents of the bulb 45 would be black. However, if albumin is present, the contents of the bulb 45 become cloudy and this cloudiness can be readily observed against the black background. The bulb 45 and its contents are viewed through the window 13 and a conical tube 78 which extends from this window to a point adjacent the bulb facilitates viewing said contents. The colored light 16 which is immediately above the window 13 will be black in color so that the observer knows that so long as the color of the contents of the bulb 45 match the color of the light 16, the test indicates the absence of albumin. Any variation of the color of the contents from the colored light 16 will indicate the presence of albumin in the specimen.

When the tablet B is deposited within the bulb 46 and the heater 73 actuated, the test for sugar is accomplished. If no sugar is present and presuming that the tablet includes Benedict's solution, the contents of the bulb 46 will turn blue in color. The contents of the bulb 46 are, of course, viewed through the window 14, a conical tube 79 which extends from the window to a point adjacent the bulb 46 facilitating this viewing. The colored light 17 above the window 14 is blue in color and so long as the contents of the tube 46 match this color, the observer 40 knows that no sugar is present. If there is sugar present in the specimen within the bulb 46, the color of the contents of the bulb 46 will gradually change from blue to green, then to yellow, and finally to red if the sugar content is excessive. Thus, by noting any variation in the color of the contents of the bulb 46 with relation to the color of the comparison light 17, the observer can readily determine whether the test shows the presence of sugar. To assist in observing the contents of the bulbs 45 and 46 suitable electrical lamps 80 are mounted immediately behind each bulb in a suitable bracket 81 which is secured to the panel 19.

After the tests are complete, the electrical apparatus, which will be hereinafter described in detail, actuates the water inlet valve 53 and fresh water is introduced and flushed through the tubular element 47, as well as through the bulbs 45 and 46 to thoroughly cleanse these parts. The fresh water introduced by opening of the valve 53 also flows upwardly through the conductor 71 and is sprayed into the funnel 66 through the spray pipe 69. This fresh water flows downwardly through the conductor 65 and 65 through the inlet tube 60 to thoroughly flush and clean this tube. The flushing water is then discharged through the discharge 51 of the element 47 and also through the outlet 58, from which points it escapes through the main discharge line 70 57. This arrangement provides for a thorough cleansing of the bulbs 45 and 46, as well as of the inlet tube 60 and tubular element 47, whereby the device is ready for the next test. It might be noted that a portion of the fresh water which 75

flushes the unit is retained within the bulbs 45 and 46, whereby the subsequent introduction of the next specimen of urine to be tested will admix with this fresh water. In this type of test it is desirable that the specimen be diluted and the retention of fresh water within the bulbs 45 and 46 accomplishes this purpose.

The apparatus is automatic in its operation and once started completes its cycle. This automatic operation is accomplished by electrical mechanism and a complete wiring diagram is illustrated in Figure 14. As shown in this figure, a main control switch 90 controls the electrical current supply through the main supply wires 90a and 90b. The switch 90 is mounted on the main support panel 19, being clearly shown in Figure 2. In addition to the main switch, a starting relay 91 is also provided and this relay is mounted on the rear side of the panel 19. The sequence of operation of the unit is controlled by an electric timing motor 92 (Figure 12) which has a plurality of timing cams 93, 94, 95 and 96, mounted on its drive shaft. The cams co-act with and control electric switches 93a, 94a, 95a and 96a, said switches including contact arms 93b, 94b, 95b and 96b, respectively, which arms ride upon the cams. The switch 93a includes contacts 93c and 93d which are arranged to be opened and closed by the arm 93b in accordance with the position of the cam 93. Switch 94a includes contacts 94c and 94d, switch 95a includes contacts 95c and 95d, while switch 96a includes contacts 96c and 96d. The contacts of the switches have connection with and control the operating parts as will now be explained.

Normally the switches 93a and 94a are open, while the switches 95a and 96a are closed. The push button 18 in the front of the closure or cover 11 is the means which starts the unit into operation and as shown in Figure 14 one contact of the push button is connected through wire 18a, with one side 96a of the main current supply. The other contact is connected through a wire 18b, with one side of a coil 91a in the starting relay 91. The opposite side of the coil is connected through wire 92a with the contact 95d of the switch 95a, which switch is normally closed. The other contact 95c of switch 95a has a connection through a wire 95e to the other side 90b of the main current supply. Normally, the push button 18 is disengaged from its contacts so that the circuit is broken by the wires 18a and 18b; depression of the button 18 closes the circuit through the closed switch 95a to the coil 91a of the starting relay. When the coil 91a is energized, the armature 97 of the starting relay 91 is moved to close a connection between two pairs of contacts. The relay 91 includes contacts 97a and 97b, as well as contacts 97c and 97d. Movement of the armature connects contacts 97a with 97b and through another switch arm connects contacts 97c and 97d. When this occurs a circuit is closed through the relay 91 to the timing motor 92, this circuit being through a wire 97e which extends from the main supply wire 90a to contact 97d. From this contact the current is conducted through a wire 97f to contact 97a and to contact 97b. From this point the current flows through a wire 97g to the side 92b of the timing motor 92. The other side of the timing motor is connected through a wire 92c with the opposite side 90b of the main current supply.

At the same time that the timing motor 92 is started, the lights 80 behind the bulbs 45 and 46, as well as the comparison lights 16 and 17

which are in the hinged cover 11 are lighted. One side of the lights 80 is connected through a wire 80a to wire 90b while the opposite side is connected through a wire 80b to the conductor 97g and back to contacts 91a, 97b and wires 91f and 91e to the opposite side 90a of the main current supply. The lights 16 and 17 are also connected, through a wire 17a and wire 95e to the side 90b and through a wire 17b to the conductor 97g. Thus, when the motor is started 10 the lights 16 and 17 in the cover, as well as the lights 80 behind the bulbs 45 and 46, are lighted. In order to maintain the coil 91a of the starting relay energized after the push button 18 is released, the contact 97c of the relay is connected through the wire 96e to the conductor 18b which connects to one side of the coil 91a. This wire 96e is also connected to a wire 96f which leads to the contact 96c of the normally closed switch 96a. The other contact 96d is connected through a wire 96g to one side of the solenoid 29 which actuates the ejector. The other side of the solenoid is connected through a wire 29a with one side 90b of the current supply. Therefore, when the starting relay is first actuated and a circuit 25 is established between the contacts 97c and 97d, an electrical circuit is closed to the operating solenoid 29 to actuate the ejector and deposit the tablets within the bulbs 45 and 46. Closing of the contacts 97c and 97d of the starting relay 30 also close an electrical circuit through wires 72a and 73a to the heaters 72 and 73, whereby these heaters are energized and heat the bulbs 45 and 46. At the same time a circuit is closed through the wire 96e to the coil 91a of the starting relay so that after the operator releases the starting button 18, the timing motor 92 will continue to 35 operate.

After operation of the solenoid 29, lighting of the lights, heating of the heaters, and starting of the motor, all of which occurs simultaneously with the actuation of the starting relay, the motor continues to operate and this causes the cams 93 to 96 to be gradually rotated. The next occurrence in the cycle of operation is the opening of the switch 96a, whereby the contacts 96c and 96d are separated. This action breaks the circuit to the solenoid 29 and it is pointed out that the cam 96 which controls the switch 96a is so adjusted that said switch is opened almost immediately after the timing motor begins operation. It is apparent that the solenoid 29 need be energized only momentarily and when the current is shut off the spring 34 will return the slide ejector to its original position.

As the motor continues to operate and when the heaters 72 and 73 have been energized for a sufficient length of time to properly heat the contents of the bulbs, the switch 95a is opened to separate the contacts 95c and 95d and break the circuit to the starting relay 91, whereby current to the heaters is cut off. Simultaneously with the opening of the switch 95a, the switch 93a is closed to connect its contacts 93c and 93d. When the starting relay 91 was de-energized by opening of the switch 95a, the current flow to the timing motor 92 was shut off through the relay and in order to maintain the current flow to the motor, the switch 93a closes to maintain a supply of current to the motor. This supply flows from the main wire 90a through a wire 93e to contact 93c, thence from contact 93d through wire 93f and wire 97g to the motor. Thus, it becomes apparent that the closing of switch 93a prevents the timing motor from being 70 75

stopped upon opening of the relay 91 which cuts off the heaters.

The motor 92 continues to operate while the tests being made in the bulbs 45 and 46 are being observed and after completion of the tests, the timing cam 94 of the switch 93a actuates the switch to close the same. When this occurs an electrical circuit is closed through the wire 95e, contacts 94c and 94d and a wire 94e to the operating solenoid 54 of the water inlet valve 53. The opposite side of the solenoid has connection through a wire 54a with the opposite side of the main current supply. Obviously actuation of the water valve flushes the unit so that said unit is ready for the next operation. As soon as flushing is complete, the cams 93 and 94 are so arranged as to reopen the switches 93a and 94a which opens the circuit to the water valve relay 54 and to the timing motor 92, whereby said motor is halted in its operation. Just as the switches 93a and 94a are opened to stop the motor 92, the cams 95 and 96 function to again close the switches 95a and 96a, whereby all parts are in position for the next tests.

Although a push button 18 which is manually operated has been shown, it may be desirable to actuate the device by the insertion of a coin and in Figure 15 a coin chute 100 is illustrated. This coin chute is mounted in the front cover 11 of the device and has contacts which connect to the wires 18a and 18b of the wiring diagram. When the coin is introduced into the coin chute said coin rolls downwardly therein and is momentarily stopped adjacent the contacts by a spring member 101 and said coin functions to close the electrical circuit between the wires 18a and 18b. It is apparent that in this instance the coin acts exactly in the same manner as the manually depressible push button.

In the operation of the apparatus, the specimen of urine to be tested is poured into the receiving funnel 66 and flows downwardly through the conductor 65 and into the inlet tube 60. From this tube a portion of the specimen enters the bulb 45 through the leg 61, while a predetermined volume enters the bulb 46 through the flask 63. It might be noted that the volume of the urine is not critical with respect to the albumin test but in order to obtain the same test upon each operation, with regard to the presence of sugar, the volume of the urine introduced into the bulb 46 should be controlled and the flask 63 accomplishes this result.

After the specimen has been introduced into the bulbs 45 and 46, the manually operated push button 18 is depressed or a coin is inserted to close a circuit to the starting relay 91. As explained, the actuation of the starting relay lights the comparison lights 16 and 17, as well as the lights 80 behind the bulbs; the starting relay also energizes the heaters and operates the solenoid 29 which actuates the ejector. Actuation of the ejector deposits a tablet A in the bulb 45 and a tablet B in the bulb 46 whereby the test may be made by the chemical reaction of the tablets which are so introduced. The heaters 72 and 73 remain on for a sufficient length of time to bring the heat of the contents of the bulbs to a desired point and are then shut off. When the heaters are shut off, the test is complete and the observer may view the contents of the bulbs 45 and 46 through the windows 13 and 14. By comparing the color of the contents of the bulbs with the color comparison lights 16 and 17, a novice may readily determine the presence of either

albumin or sugar in the specimen. The timing motor 92 is so adjusted that sufficient time for observance of the color of the contents of the bulb is permitted. After this time has elapsed, the water inlet valve 53 is electrically actuated to admit the fresh water for flushing purposes. As explained, this fresh water flows through the tubular element to thoroughly flush out the bulbs 45 and 46. A portion of the fresh water is conducted upwardly through the conductor 71 and is ejected into the receiving funnel 66 from the spray 69. This fresh water then flows downwardly to thoroughly cleanse and flush the inlet tube 60. After the flushing operation is complete, the timing motor is halted and the machine is ready for the next operation.

The apparatus is relatively simple in construction and is entirely automatic in its operation. Any person regardless of their unfamiliarity with urinalysis tests can make the test and accurately determine the result. Substantially all of the operating mechanism is mounted on the single supporting panel 19 which makes it possible to readily remove the panel and thereby remove the contents of the casing. In addition, the tubular element 47 which includes the bulbs 45 and 46 is maintained in position by spring clips so as to be readily removed. The use of the tablets facilitate handling of the chemicals which are necessary for the tests. The tablets are mounted within tubes which are easily removable from their spring clip holders. As previously noted the particular tablets which are used are subject to variation.

As an illustration of the general type of tablet to be used in the albumin test, a composition of sulfasalicylic acid and a small amount of boric acid may be pressed together to form the tablet.

The purpose of the boric acid is to assist in releasing the tablet from the dies forming the same.

The tablet for the sugar test may comprise sodium citrate, sodium carbonate and copper sulphate in the following proportions:

	Percent
Sodium citrate	47.5
Sodium carbonate	40.5
Copper sulphate	12.0

With this composition, any desired or suitable quantity of talcum or boric acid may be used and acts as a filler or lubricant for the stamping dies to assure release of the tablet therefrom.

The foregoing compositions are set forth as illustrative and it is within the scope of the invention to employ any other material in tablet form for making sugar and albumin tests.

It is noted that it is desirable to avoid absorption of moisture by the tablets while they are in position within the tubes 37 and 38 and if the heat which is radiated by the lamps 80 is not sufficient to maintain the interior of the casing dry, additional electrical heating lamps may be mounted on the panel or support 19 adjacent the tubes. Also, it may be desirable to construct the tubes 37 and 38 of a red or black glass to enhance their heat radiating qualities.

The foregoing description of the invention is explanatory thereof and various changes in the size, shape and materials, as well as in the details of the illustrated construction may be made, within the scope of the appended claims without departing from the spirit of the invention.

What I claim and desire to secure by Letters Patent is:

1. A urine testing device including, a casing, a pair of test receptacles within the casing, each having an open upper end for receiving a specimen of urine to be tested, a pair of chemical tablet containers one for each receptacle mounted 5 above the receptacles and having chemical tablets therein, an ejector mechanism interposed between the outlet end of each container and the receptacle associated with said container, said ejector mechanism including means for delivering 10 one tablet from each container into the open upper end of its associated receptacle upon each operation of said ejector mechanism, actuating means within the casing connected with each ejector mechanism for operating the same, heating 15 means adjacent each receptacle for heating the contents of the receptacle, control means for said heating means for operating said heating means to heat the contents of the receptacles subsequently to the delivering of a chemical 20 tablet to each receptacle by the ejector mechanism, whereby the specimen within the receptacles is subjected to test in accordance with the chemical within said receptacles, said pair of test receptacles being spaced from each other 25 in the same horizontal plane, a tubular connection extending between the receptacles and communicating with the receptacles intermediate the upper and lower ends of the receptacles, whereby the connection establishes communication between the receptacles and also whereby the receptacles and connection form a single unitary structure, and means within the casing for detachably mounting said unitary structure within the casing to facilitate its removal for cleaning 30 purposes.

2. A urinalysis device including, a casing, a plurality of test receptacles within the casing for receiving a specimen of urine to be tested, a viewing window in the casing aligned with each receptacle and through which the receptacle is visible from the exterior of the casing, whereby the contents of the receptacles may be observed from the exterior of the casing, a plurality of chemical tablet containers mounted within the casing above the receptacles with the number of containers being the same as the number of receptacles, each container having its tablets being adapted to be deposited into one of the receptacles, a single ejector disposed between the outlet ends of the tablet containers and the receptacles into which the tablets from such containers are to be deposited, actuating means for operating the single ejector to simultaneously eject one tablet from each container and to deposit the tablet 55 from each container into its respective receptacle, an inlet conduit extending into the casing and communicating with the receptacles for receiving the specimen to be tested and for conducting it to the receptacles, said test receptacles being two in number and being spaced from each other in the same horizontal plane within the casing, a tubular connection extending between the receptacles and communicating with each receptacle intermediate the upper and lower ends thereof, whereby the connection establishes communication between the receptacles and also whereby the receptacles and connection form a single unitary structure, and means within the casing for detachably mounting said unitary structure within the casing to facilitate its removal for cleaning 60 purposes.

3. A testing device of the character described including, a casing, a support within the casing, a pair of test receptacles mounted on said support in the same horizontal plane and spaced

from each other and having their upper ends open, a tubular connection intermediate the ends of the receptacles and establishing communication therebetween, an inlet in the casing for introducing a fluid specimen to be tested, a tubular inlet element mounted within the connection between the receptacles connected with the inlet and having its discharge ends located above the receptacles for directing the specimen into said receptacles, means within the casing for introducing a chemical reagent into each receptacle, means adjacent each receptacle for heating the contents thereof after the chemical reagents have been added whereby the specimen within the receptacles is subjected to tests in accordance with the chemical reagents therein, and means for introducing a flushing fluid through the tubular inlet element whereby the flushing fluid flows through the tubular connection and through the receptacles to empty and cleanse said receptacles after the tests are complete.

4. As a sub-combination in a urinalysis device, a pair of test receptacles having their central

portions connected by a tubular conductor and having their upper ends open, an inlet tube disposed longitudinally within the conductor and having its ends projecting into the receptacles whereby fluid introduced into the tube will flow into the receptacles, and an enlarged flask at one end of the tube and having a restricted outlet, for controlling the volume of fluid which flows from the tube into the test receptacle adjacent thereto.

WOLF GOODMAN.
